GLASS CHANNEL RUN

Harold G. Hencken, Greenwich, Conn., assignor to American Felt Company, Glenville, Conn., a corporation of Massachusetts

Application May 21, 1957, Serial No. 660,658

1 Claim. (Cl. 296—44.5)

This invention comprises a new and improved lining for glass channel runs of the type commonly employed for slidably retaining a glass plate in the door or body of an automobile.

Heretofore strips of felt have been attached to the inner surface of a U-shaped channel and this construction has not been entirely satisfactory because the felt strips tend to swell in contact with water and variations in thickness of the felt cause variations in the frictional resistance to movement of the glass plate. Moreover, when square cut edges of the felt strips are exposed they interfere with rapid assembly of the glass components. Felt strips also tend to buckle when the channel is bent or curved, and when attached by a sewed seam the thread is exposed to wearing surfaces. In glass runs heretofore known it has proved impractical to use felt of dense consistency because of increased frictional resistance incident to its use.

The improved lining of the present invention eliminates the above objections and makes use of the bending resilience of wool felt or other non-woven or woven fabric or composition rather than the compression resistance of the material. To this end the lining comprises sheet felt located at opposite sides of the channel in involute loop formation with the side members of the loops resiliently spaced apart but compressible toward each other. Thus the resilient compressibility of the felt is utilized to maintain effective sealing contact with the glass plate with a substantially uniform degree of frictional engagement under all weather conditions encountered. Thus a denser fabric may be used which has greater dimensional stability and may be manufactured to closer tolerances. Resistance to movement of the glass plate is reduced due to lessening of contact pressure between the glass and the fabric. A rounded or tapered outer edge is provided for automatic centering of the glass plate during assembly. If stitching is employed to join the inner folds of the fabric it is not visible and not exposed to wear. The use of thinner fabric with spaces resiliently maintained between the folds thereof allows the lining to be applied to a curved channel without buckling. Accordingly, the lining may be smoothly cemented to the inner face of the channel and its cut edge may be conveniently enclosed and concealed within a metallic bead.

These and other features of the invention will be best understood and appreciated from the following description of certain preferred embodiments thereof selected for purposes of illustration and shown in the accompanying drawings in which:

Figs. 1-6 are views in cross-section on an enlarged scale through a conventional channel lined in specifically different formation, and

Fig. 7 is a chart indicating the comparative compression strain upon solid felt, pile fabric and felt disposed in involute loop formation.

As shown in Fig. 1 the channel itself or the casing 10 of the channel is formed of sheet metal bent into U-shape with an inner facing 11 of fabric or plastic sheet mate-

2

rial. Within this is placed a molded rubber filler 12 which may be .04" or thereabouts in thickness. A sheet of felt 13 is formed to fit within the rubber filler and given an involute fold or Z formation in each side; that is to say, it is folded to present a downwardly opening loop 14 and an overlapping upwardly opening loop 15, and these loops are secured together by a line of stitching 16. The free margins of the felt sheet then extend upwardly concealing the edges of the rubber filler 12 and are engaged along the opposite walls of the channel within a cylindrical metallic bead 17 which engages also the upper edges of the casing 10 and its inner facing 11.

In Fig. 1 is shown the normal uncompressed shape of the involute loop formation from which it will be apparent that the side walls of the loops are resiliently spaced apart. In Fig. 2 a portion of the glass plate is indicated in dot-and-dash lines as received between the involute loop formation of the sheet felt and from this it will be apparent that the loops are somewhat compressed or consolidated by the action of the glass. The three side portions of the two loops are arranged in superposed relation and are compressible as a stack on opposite sides of the glass plate. This compression takes place as already explained without substantially increasing the frictional resistance to movement of the glass while in contact with the felt.

In Figs. 3 and 4 are shown a modified construction in which the rubber filler 12 of Figs. 1 and 2 is omitted and sheet felt 13' of considerably greater thickness than that already described is employed. It is, however, fashioned in the same involute or Z loop formation presenting a downwardly opening loop 14' and an overlapping upwardly opening loop 15'. In Fig. 4 the compressive action of the glass plate upon the involutions of the felt formation is indicated. In both examples the felt is formed from a continuous sheet that extends without interruption across the bottom of the channel. In a channel of commercial size such as that shown in Figs. 1 and 2, a strip of felt 2.5" wide and .036" in thickness may be used to advantage.

In the channels of Figs. 3 and 4 the rubber filler is omitted and the felt increased to about $\frac{3}{16}$ " in thickness. The sheet felt as shown in these figures has an involute fold at each side of the channel including the downwardly opening loop 14' and the overlapping upwardly opening loop 15', the side portions of which are resiliently spaced apart but compressible when the glass is inserted between them.

Figs. 5 and 6 suggest further modifications of the invention in which separate sheets or strips of felt are employed at opposite sides of the channel. In the left side of Fig. 5 the felt strip 19 is given an involute fold having a downwardly opening loop 20 enclosed in an upwardly opening loop 21. A rubber filler 12 is shown in this side of the channel. In the right side of Fig. 5 the rubber filler is omitted and the thickness of the felt somewhat increased.

In Fig. 6 the rubber filler 12 is shown and the felt strips 22 are folded to present a single upwardly opening loop 23, the sides thereof being resiliently spaced in initial condition but arranged to be compressed by the action of the glass plate. In both of these modifications a block or strip is secured to the bottom of the channel.

In each of the illustrated embodiments of the invention the marginal portions of the felt sheet or strips are extended outwardly at an inclination and in divergent relation beyond the side walls of the channel thereby facilitating the centering of a glass plate therein.

Fig. 7 indicates graphically the action of solid felt strip, pile fabric and felt presenting involute folds. The deformation of these materials is plotted in the abscissa axis

in .001" of deformation and in the ordinate axis as pounds of deforming pressure per lineal inch of the strip. The chart makes it apparent to a striking degree that deformation of the involute folded felt requires very substantially less pressure than the solid felt strip or to be 5 equivalent to pile fabric as an initial deformation of .060" has been reached.

Having thus disclosed my invention and described in detail illustrative embodiments thereof, I claim as new and desire to secure by Letters Patent:

In a glass run window channel, a lining comprising a single continuous sheet of felt folded in Z-formation at each side of the channel, presenting rounded outwardly directed entering edges and extending without interruption across the bottom of the channel, the inner folds of 15 each Z-formation being connected together within their

outer folds, and the outer folds being readily conformable until consolidation with the inner folds.
